LIFTING JACK

Charles E. Branick, Fargo, N. Dak.

Application June 24, 1953, Serial No. 25,628

Term of patent 14 years

(Cl. D41—1)

To all whom it may concern:

Be it known that I, Charles E. Branick, a citizen of the United States, residing at Fargo, county of Cass, and State of North Dakota, have invented a new, original, and ornamental Design for a Lifting Jack, of which the following is a specification, reference being had to the accompanying drawing, forming a part thereof.

Fig. 1 is a perspective view of a lifting jack, showing my new design;

Fig. 2 is a view in plan;

Fig. 3 is a view in side elevation; and

Fig. 4 is a view in end elevation as seen from the right to the left with respect to Fig. 3.

I claim:

The ornamental design for a lifting jack, as shown.
